 The Wilcolator Company, a corporation of Del-
 aware

Application July 30, 1938, Serial No. 222,134

12 Claims. (Cl. 200—138)

This invention relates to temperature regulators and has particular reference to a novel device of this character which is reliable and efficient in operation, has a simple, durable and compact construction, and may be manufactured at low cost.

One feature of the present invention resides in the provision of a novel temperature regulator comprising a pair of opposed bimetallic members so arranged that they bow in opposite directions in response to a change in temperature, and a flexible strip disposed intermediate the members and operatively connected at one end to adjacent ends thereof. The flexible strip and the bimetallic members are preferably arranged in generally parallel relation and supported on a common mounting, so that when the members bow in response to a change in temperature their effective lengths are shortened, with the result that the flexible strip is compressed endwise. Under this compressive action, the flexible strip bows, whereby the intermediate part thereof moves laterally and causes actuation of a valve, a switch, or the like. It will be apparent that by employing two bimetallic members in opposed relation, the tendency for each of them to move the end of the flexible strip laterally when the member bows or straightens, is opposed by the other, so that flexing of the members is effective only in compressing the flexible strip endwise or releasing it. Accordingly, the strip is held at all times against any substantial lateral movement relative to the control means.

In the preferred form of my new device, the flexible strip is backed intermediate its ends by a stop, which may be part of the valve or switch controlled by the strip, and is so arranged that it is forced against the stop with increased pressure as it is bowed, until the strip assumes a wave-shape of unstable equilibrium. The strip then snaps away from the stop to a bowed form of opposite curvature, thereby operating the switch or other control element with a snap action. The bimetallic members are preferably connected to the snap strip by bending adjacent ends of the members inwardly over the corresponding end of the strip, so that flexing of the members results in a force transmitted through the bent ends thereof to the strip. With this construction, compression of the strip is effected not only by bowing of the intermediate portions of the bimetallic members and consequent shortening of their effective lengths, but also by the change in the angles of their bent ends which become more acute when the members bow.

Another feature of the invention resides in the provision of a temperature regulator comprising novel adjustment means for controlling the temperature at which the regulator operates. The adjustment means includes a handle mounted on a frame or casing and operatively connected to a screw threaded in the frame, the screw coacting with a mounting for one end of a flexible strip which actuates a switch, or the like. The flexible strip is adapted to be compressed endwise and bowed by a thermo-responsive means engaging the opposite end thereof, and the compression of the strip may be varied independently of the thermo-responsive means by operating the handle and thereby turning the screw and adjusting the mounting.

Preferably, the connection between the handle and screw may be rendered inoperative so that movement of the handle has no effect on the mounting, and to this end the screw may be threaded through a nut adapted to turn with the screw and handle but normally held against rotation by releasable locking means, whereby operation of the handle causes the screw to move axially in the nut. When the locking means is released, however, operation of the handle causes the screw and nut to turn together, so that no axial movement of the screw is obtained. This construction is of particular advantage in calibrating the instrument, since calibration may be effected by simply adjusting the screw in the nut until the switch or valve is in the desired position at room temperature of the thermo-responsive means, then releasing the locking means and adjusting the handle until it is in the position indicating room temperature, and thereafter locking the nut against rotation. Further operation of the handle will then move the screw axially in the nut and adjust the mounting, so that the actuating strip operates at the desired temperature.

Still another feature of the invention is in the provision of novel means coacting with the adjustment means for indicating whether the switch or other control element is in its open or its closed position. The indicating means includes a lamp bulb or other light source mounted inside or behind the handle, the latter being transparent or translucent so that light from the source is visible therethrough. The light source may be energized by a circuit which includes the adjustment screw, the flexible strip, and the switch or valve element actuated by the strip, so that the light source is energized or de-energized according to the position of the actuating

strip with respect to its coating control element. Preferably, the lamp bulb is rotatable with the handle and adjustment screw, and when the actuating strip is used to control a switch, a cam is provided which also rotates with these parts and controls a master switch.

These and other features of the invention may be better understood by reference to the accompanying drawings illustrating an embodiment of the invention adapted for controlling electric circuits. It will be understood that while the principles of the invention are described specifically hereinafter in connection with an electric regulator, they are not limited to regulators of this type but are applicable to gas and other regulators as well. In the drawings:

Fig. 1 is a front view of one form of the new regulator;

Fig. 2 is a vertical, longitudinal section through the regulator shown in Fig. 1;

Figs. 3 to 7, inclusive, are sections on the lines 3—3 to 7—7, respectively, in Fig. 2;

Fig. 8 is a plan view of the regulator shown in Fig. 1;

Fig. 9 is a section through part of a slightly modified form of the regulator;

Fig. 10 is a detail view of a part of the adjustment and indicating means;

Figs. 11 and 12 are detail views of one of the conductors;

Fig. 13 is a schematic view of a circuit for use with the regulator shown in Figs. 1 to 8;

Fig. 14 is a schematic view of a circuit for use with the regulator shown in Fig. 9;

Fig. 15 is a diagrammatic view of the opposed, bimetallic members, showing them in different operating positions, and

Fig. 16 is a diagrammatic view of the flexible strip, showing it in different operating positions.

Referring to the drawings, the regulator shown in Figs. 1 to 8 comprises a casing 20 open at the bottom and made of insulating material, and a bracket 21 having a leg 21' which extends into the casing through a slot in the top thereof and lies against the front wall of the casing, the leg being held securely in grooves 22 in the sides of the casing, as shown in Fig. 3. Near its outer end, the bracket carries a thumb screw 23 threaded therein and adapted to clamp the casing to a suitable support.

Mounted inside the casing is a metal bracket 24 having one leg secured to the top of the casing by a binding post 25, the other leg 24' extending downwardly in spaced relation to the front wall of the casing. A contact arm 26 made of spring metal is seated in the casing in a recess formed in the top thereof above the bracket 24. The front part of the contact arm carries a contact 27 and is offset downwardly from the top of the casing and disposed in an opening 28 in the bracket 24. A piece of insulating material 29 is interposed between the contact arm 26 and bracket 24.

Below the contact arm 26 is a bus bar 31 secured to the top of the casing by a binding post 32, the bus bar being insulated from the contact arm and bracket 24 by a sheet of insulating material 33. The bus bar extends forwardly in spaced, parallel relation to the spring arm and carries near its front end a contact 34 directly below contact 27. The top of the casing is formed with an opening 35 over contact arm 26, and mounted in the opening is a metal bushing 36 which extends downwardly through the contact arm, the bracket 24, the bus bar, and the

insulating members, the top of the bushing being formed with a head which seats on the contact arm. A collar 36' of insulating material surrounds the bushing and serves to insulate the latter from the bracket 24 and bus bar 31. The bushing is externally threaded and has a nut 37 screwed on the lower end thereof and clamped against an insulating washer 38 which is interposed between the nut and the bus bar 31, the nut being held against rotation by a downwardly projecting ear 31' on the bus bar (Figs. 11 and 12) which engages one edge of the nut. A screw 39 is threaded through the bushing and forms at its inner end one contact of a switch.

The other switch contact is designated by the numeral 41 and is carried by a flexible strip of sheet metal 42. The strip 42 is adapted to be compressed endwise and bowed by thermo-responsive means comprising two strips of bimetal 43 and 44 arranged in opposed relation with the metal having the higher coefficient of expansion on the outside. The strips of bimetal are generally parallel, although they are normally bowed outwardly intermediate their ends, and their front ends are connected to the leg 24' of bracket 24 by integral studs 24'' on the sides of the bracket which extend through the bimetallic members and are upset at their ends. A metal strap 45 has its ends secured at the sides of bracket leg 24' between the latter and the bimetallic strips 43, 44. The strap extends rearwardly from the bracket leg and is formed intermediate its ends with a flat, vertical surface forming a mounting or seat for the front end of the flexible strip 42. The latter is bifurcated at its front end, as shown at 42', and the bifurcations extend through slots 45' formed in strap 45 at each side of the flat seat, whereby the flexible strip 42 is held by the strap 45 in a plane transverse to the faces of the bimetallic members. From the bracket leg 24', the bimetallic members 43 and 44 extend rearwardly and terminate in end portions 43' and 44', respectively, which are bent inwardly and then forwardly. The ends of the members are slotted and fit into notches 43'' and 44'', respectively, in the rear end of flexible strip 42.

The mounting for the flexible strip 42 is adjustable by means comprising a square headed screw 47 extending rearwardly through an enlarged opening in bracket leg 24' and adapted to engage the flat seat of strap 45. A nut 48 is threaded on the end of screw 47 and is held against the rear face of bracket leg 24' by a locking screw 49 which is threaded through the bracket leg with its head engaging the rear face of the nut. The locking screw 49 is normally tightened against nut 48 to prevent rotation of the latter, so that when adjustment screw 47 is rotated, it moves axially in the nut, whereby the mounting for strip 42 may be adjusted. However, when locking screw 49 is loosened, rotation of adjustment screw 47 permits the nut 48 to turn with it, so that there is no adjustment of the mounting.

The adjustment screw 47 is rotatable by a member 50 made of insulating material and provided with a square, central bore 50' in which the head of the adjustment screw is closely fitted. A metal collar 52 closely surrounds the front end of member 50 and is formed at its rear with a flange seated against a shoulder on the member 50 and with a pair of prongs 52' extending into recesses in the member. The collar 52 extends forwardly through a metal sleeve 53 fitted in aligned openings in the bracket leg 24' and the

front wall of the casing, and the collar is rotatable in the sleeve to turn the insulating member 50 and adjustment screw 41. Rotation of collar 52 is effected by means of a handle 54 formed with a central bore 54' and fitted tightly on the front end of the collar, the handle being held on the collar by a detent 52" on the collar which engages in a suitable recess in the handle. The handle 54 is made of a translucent or a transparent material and is provided on its front face with an indicating arrow 54' cooperating with temperature graduations 55 marked on the front wall of the casing or on a suitable dial, not shown.

The position of switch 39, 41 may be indicated by means comprising an incandescent lamp bulb 57 located in the collar 52 and the central bore of the handle. Intermediate its ends, the collar 52 is formed with circumferentially spaced ears 58 which are struck inwardly from the cylindrical surface of the collar and extend rearwardly, as shown particularly in Figs. 4 and 10. The base of the lamp bulb is clamped between the ears 58 and has a pin 57' which engages in a notch formed in the rear end of one of the ears (Fig. 2), and the lamp bulb may be removed from the collar by pressing it inwardly to release the pin 57' from the notch in the ear, and then rotating the bulb and withdrawing it from the front end of the collar. A metal eyelet 59 extends through the front end of the rotatable member 50 between the bore 50' and the interior of collar 52, and the front end of the eyelet is normally urged against the base contact of the lamp bulb by a coil spring 60 seated in bore 50' between the rear end of the eyelet and the head of adjustment screw 41.

The rotatable member 50 is adapted to actuate the contacts 27, 34, and to this end it is formed with a cam 62 (Fig. 5) adapted to engage an extension 26' of contact arm 26. The extension 26' is curved transversely, as shown in Fig. 5, and engages one side of cam 62 when the handle is in its off position, whereby the contact arm 26 is elevated so as to disengage contacts 27 and 34. When the handle is turned in a clockwise direction from its off position, the top of cam 62 rides under the extension 26' so as to elevate it further and then allow it to snap downwardly and engage contacts 27 and 34. Rotation of the handle 54 is limited by a finger 63 on the rotatable member 50, adapted to engage a stop 64 formed on the inside of the casing.

The flexible strip 42 is of such a form and is so positioned that it is normally bowed slightly against the contact screw 39, whereby the strip assumes a wave-shape, as shown in exaggerated form in Fig. 16. When the temperature rises, the bimetallic members bow and cause their intermediate parts to move outwardly and assume a more pronounced bow-shape, and at the same time the bent ends of the members move inwardly at a more acute angle with respect to the intermediate parts of the members as shown diagrammatically in Fig. 15. The flexible strip 42 is thus compressed not only by the tendency for the bimetallic members to shorten their effective lengths incident to bowing thereof, but also by the change in the angle of the bent ends of the members. As the strip 42 is compressed endwise, it is forced against screw 39 with greater pressure so that its wave-form becomes more pronounced, until it attains a condition of unstable equilibrium. Thereupon, it moves away from contact screw 39 with a snap action to the bowed form shown by the dotted line in Fig. 16.

When the temperature decreases, the bimetallic members 43 and 44 flex to the full line positions shown in Fig. 15, thereby gradually releasing the endwise compression of strip 42. As soon as the compression in the latter is released sufficiently, the tendency for the strip to assume its initial position asserts itself, and the strip then snaps back against the contact screw 39 to the full line position shown in Fig. 16.

The temperature at which the bimetallic members 43 and 44 operate the snap strip 42 may be adjusted by turning handle 54 and thereby rotating adjustment screw 41 through collar 52 and the insulating member 50. When the handle is turned in a clockwise direction, the adjustment member 41 is screwed inwardly in nut 48 so as to increase the initial compression in flexible strip 42, whereby the latter will snap away from contact screw 39 at a lower temperature. Conversely, when the handle is turned in a counter-clockwise direction, the screw 41 is moved away from strip 42 so as to decrease the initial compression therein, whereby a higher temperature is required to flex the bimetallic members sufficiently to operate the flexible strip and open the contacts.

It will be apparent that a conducting path is traceable from binding post 25 through bracket 24 to flexible strip 42 by way of the parallel paths consisting of the nut 48 and adjustment screw, the strap 45, and the bimetallic members 43 and 44. From the contact 41 on flexible strip 42, the conducting path continues through screw 39, bushing 36, contact arm 26, contacts 27 and 34, bus bar 31, to the other binding post 32. The conducting path described may be broken by turning handle 54 to its off position, wherein contacts 27, 34 are separated by cam 62, or as a result of the bowing of flexible strip 42 away from screw 39. A conducting path is also traceable from binding post 32 through bus bar 31, contacts 34 and 27, contact arm 26, screw 39, flexible strip 42, adjustment screw 41, coil spring 60, eyelet 59, lamp 57, collar 52, sleeve 53, and bracket 21 which may be clamped to a suitable ground connection.

For illustrative purposes, the conducting paths described above are illustrated diagrammatically in Fig. 13 in a control circuit for a heater of the type commonly used in vehicles and including an electric motor as the principal operating element. It is to be understood, however, that the new regulator may be used for the control of other devices as well. Referring to Fig. 13, the battery 66 of the vehicle has a wire 67 leading from the positive terminal thereof to the binding post 32, and another wire 68 leading from the negative terminal to a ground connection 69, preferably the metal frame of the vehicle to which the clamp 21 is likewise connected. From the wire 68, another wire 70 leads to one side of the electric motor 71 which operates the heater, and the other side of the motor is connected through a wire 72 to binding post 25.

When the handle 54 is in its off position (Fig. 5), the contacts 27 and 34 are separated so that the conducting path from the positive side of the battery to the motor 71 is broken. In this position of the handle, the conducting path from the positive side of the battery to the lamp 57 is likewise broken by contacts 27, 34. When the handle is turned in a clockwise direction from its off position, it permits contacts 27, 34 to close and also screws the adjustment member 41 toward the flexible strip 42. Upon closing of con-

tacts 27, 34, a circuit is established which is traceable from the positive side of the battery through wire 67, binding post 32, bus bar 31, contacts 34 and 27, contact arm 26, screw 39, flexible strip 42, bracket 24, binding post 25, wire 72, motor 71, wires 70 and 68, to the negative side of the battery, whereby the motor is energized and the heater started in operation. Simultaneously, another circuit is established which is traceable from the positive side of the battery through binding post 32 and flexible strip 42, adjustment screw 47, lamp 57, bracket 21, the frame of the vehicle, ground connection 69, wire 68, to the negative side of the battery. The lamp 57 is thus energized and light rays therefrom pass through the handle 54 so as to inform the operator that the heater is functioning. Thereafter, the handle 54 is set to the desired temperature indicated by the graduations 55.

As the temperature rises, due to operation of the heater, the bimetallic members 43 and 44 bow and gradually increase the compression of strip 42 and finally cause the latter to snap away from contact screw 39 at the temperature for which the handle is set. Thereupon, the conducting path from the positive side of the battery to the motor 71 is broken by the contacts 39, 41 and the heater is stopped. Also, the conducting path from the positive side of the battery to the lamp 57 is broken by these contacts, so that the lamp is de-energized, thus indicating to the operator that the heater is no longer in operation. As the temperature decreases, the bimetallic members 43 and 44 gradually release the compression in strip 42 and finally permit the latter to snap back to its initial position against contact screw 39, whereby the motor 71 is once more energized and the lamp 57 illuminated. The heater may be shut off at any time by turning the handle 54 in a counterclockwise direction to its off position, thereby opening the contacts 27, 34 and breaking the circuits through the motor and indicating lamp.

It will be observed that the new regulator is simple and compact in construction and has only a few moving parts. By arranging the bimetallic members 43 and 44 in opposed relation, the tendency for each of them to move the notched end of strip 42 laterally is opposed equally by the other, so that the resultant of the forces exerted by the members when heated is an endwise thrust on the flexible strip. Accordingly, the contact 41 is maintained in alignment with contact screw 39 at all times. Since the contact 41 is snapped by the flexible strip into and out of engagement with contact screw 39, arcing between the contacts is prevented. The contact screw 39 may be readily adjusted in bushing 36 to obtain the desired snap action of the flexible strip 42. Calibration of the device may be effected easily by adjusting the handle 54 until the adjustment screw 47 maintains strip 42 under the desired amount of compression at room temperature, then loosening the locking screw 49 and turning the handle to the position indicating room temperature, and then tightening the locking screw 48.

In the illustrated embodiment of the invention, the screw 47 serves not only as an adjustment means for controlling the operating temperature of the snap strip 42, but also as part of the conducting path leading through the insulating member 58 to the indicating lamp 57. The member 58, in turn, serves not only to transmit rotation

of the handle to adjustment screw 47 and to house the conductors between the lamp base and the adjustment screw, but also to control the cut-off switch composed of contacts 27 and 34 and to limit the rotation of the handle by coaction with stop 64. In addition, the bracket 21 performs the dual function of clamping the regulator to a suitable mounting on the vehicle and providing a return path for the current which energizes the indicator 57.

In some instances, it may be desired to cause the motor 71 to rotate slowly when the flexible strip snaps away from contact screw 39, and to this end, the modified form of the regulator shown in Fig. 9 may be employed with the circuit shown diagrammatically in Fig. 14. The regulator shown in Fig. 9 is similar to that shown in Figs. 1 to 8, except that a headless screw 72 is threaded in the bushing 36 in place of contact screw 39, the screw 72 forming an adjustable, fixed contact coacting with the movable contact 41 on the flexible strip. A headed screw or binding post 73 is threaded in the top of the bushing with the end of the screw terminating in spaced relation to the top of screw 72. The screw 73 extends through a metal washer 74 and has a wire connector 75 clamped between the washer and the top of the casing over the opening 35. A lug 76 formed on the casing prevents accidental bridging of the wire connector 74 and bracket 21.

The wiring shown in Fig. 14 is similar to that shown in Fig. 13, except that a resistor 77 is connected between the binding post 73 and binding post 25. Accordingly, when flexible strip 42 is in its normal position in contact with screw 72, the motor 71 is energized through contacts 41 and 72 which short circuit the resistor. However, when the strip 42 snaps away from contact screw 72, the motor obtains sufficient current through the resistor 77 to cause it to rotate slowly until the contacts 41 and 72 are again closed, whereupon the motor is brought up to full speed.

It will be apparent that by forming the bimetallic members 43 and 44 with their high expanding elements on the inside, instead of the outside, the members will bow and break the circuit in response to a decrease in temperature and will cause the circuit to close upon a rise in temperature. With the bimetallic members so arranged, the regulator may be used for controlling cooling appliances, such as refrigerators and air conditioning apparatus. Also, the regulator may be adapted to control selectively either a heating appliance or a cooling appliance by employing a second contact screw (not shown) similar to the screw 39 but on the opposite side of the flexible strip 42 and associating with one of the contact screws a circuit for controlling a heater and with the other contact screw a circuit for controlling a cooling appliance. One or the other of the control circuits may then be rendered effective, as desired, by means of a two-way switch operable to complete a circuit through one or the other of the contact screws. Thus, when a heater is to be controlled, the circuit through the upper contact screw 39 would be effective, and when a cooling appliance is to be controlled the two-way switch would be thrown over to render the circuit through the lower contact screw effective.

I claim:

1. A temperature regulator comprising a pair of opposed bimetallic members adapted to flex in opposite directions in response to a change in temperature and having adjacent ends, a flex-

ible strip disposed between the members with one end of the strip operatively connected to said adjacent ends of the members, said members being operable conjointly on said end of the strip to move the same toward the opposite end of the strip, means for mounting said strip and members, adjustment means for compressing the strip endwise relative to said members, and control means coacting with the strip intermediate its ends.

2. In a temperature regulator, the combination of a pair of bimetallic strips arranged in opposed relation and adapted to flex in opposite directions when heated, adjacent ends of the strips being bent inwardly and back toward the opposite ends of the strips, a flexible strip intermediate the bimetallic strips and generally parallel thereto and operatively connected at one end to said bent ends thereof, and means mounting the opposite ends of said strips.

3. In a temperature regulator, the combination of a pair of bimetallic strips arranged in opposed relation and adapted to flex in opposite directions when heated, adjacent ends of the strips being bent inwardly and back toward the opposite ends of the strips, a flexible strip intermediate the bimetallic strips and generally parallel thereto and having notches in one end thereof, said bent ends of the bimetallic strips being fitted in the notches, and means for mounting the opposite ends of said strips.

4. In a temperature regulator, the combination of a supporting member, a flexible strap mounted at its ends on the supporting member, a pair of bimetallic members mounted at one end on the supporting member adjacent the ends of the strap, said bimetallic members being opposed and operable to flex in opposition directions when heated, and a flexible strip seated at one end on the strap intermediate its ends and operatively connected at its opposite end to the free ends of the bimetallic members.

5. In a temperature regulator, the combination of a supporting member, a flexible strap mounted at its ends on the supporting member, a pair of bimetallic members mounted at one end on the supporting member, said bimetallic members being opposed and operable to flex in opposite directions when heated, a flexible strip seated at one end on the strap intermediate its ends and operatively connected at its opposite end to the free ends of the bimetallic members, and adjustment means engaging the strap intermediate its ends and operable to vary the position of the intermediate part of the strap relative to the supporting member.

6. In a temperature regulator, the combination of a supporting member, a flexible strap mounted at its ends on the member and having a substantially flat seat intermediate its ends and slots adjacent the seat, a flexible strip bifurcated at one end and mounted on said seat with the bifurcations disposed in the slots, and a pair of bimetallic members mounted at one end on the supporting member and operatively connected to the free end of the strip, said members being opposed and operable to flex in opposite directions when heated.

7. In a temperature regulator comprising a flexible strip and thermo-responsive means for compressing the strip endwise and bowing it, the combination of adjustment means for varying the compression of the strip and including a nut, an adjustment screw threaded in the nut

and operatively connected to one end of the strip, said screw and nut being rotatable together, and locking means cooperating with the nut for securing the same against rotation.

8. A temperature regulator comprising a pair of opposed bimetallic members adapted to flex in opposite directions when heated, a flexible strip intermediate the members and operatively connected at one end to adjacent ends of the members, means for mounting the strip and members, said members being operable to compress the strip, a fixed contact coacting with the strip intermediate its end, a pair of contacts connected to the fixed contact, a handle for adjusting the compression in the strip, and means responsive to operation of the handle for actuating one of said pair of contacts.

9. In a regulator, the combination of a metallic supporting member, thermo-responsive control means carried by the supporting member and including a movable contact, a current conducting path connecting said contact and supporting member, a pair of contact arms on the supporting member and insulated from the member and from each other, a pair of cooperating contacts carried by said arms, a metal bushing connected to one of the arms, a screw threaded through the bushing and coacting with said first contact, and wire terminals connected to the other arm and the supporting member.

10. In a regulator, the combination of a metallic supporting member, thermo-responsive control means carried by the supporting member and including a movable contact, a current conducting path connecting said contact and supporting member, a pair of contact arms on the supporting member and insulated from the member and from each other, a pair of cooperating contacts carried by said arms, a metal bushing connected to one of the arms, a headless screw threaded in the bushing and coacting with said first contact, a binding post threaded in the bushing over said first screw, and wire terminals connected to the other arm and the supporting member.

11. In a temperature regulator comprising a thermo-responsive control means and a temperature adjustment handle for adjusting the control means to different temperature settings, the combination of an operative connection between the handle and the control means including a nut, an adjustment screw threaded in the nut and operatively connected to the control means, said screw and nut being rotatable together, and locking means cooperating with the nut for securing the same against rotation, said locking means being releasable to permit rotation of the screw and nut as a unit to calibrate the regulator.

12. A thermo-responsive regulator comprising a bimetallic member, a flexible, bowed strip adjacent and generally parallel to said member, the strip and member being operatively connected at one end, means for mounting the other ends of the member and strip, the bimetallic member being operable to compress the strip endwise to increase the bowing of the strip, temperature adjustment means at said second end of the strip adjacent the mounting means and operable to vary the position of said second end relative to the corresponding adjacent end of the bimetallic member, and control means coacting with the strip intermediate its ends.

LYNDON W. BURCH.
